GRATE

Harold Thomas Henry, New York, N. Y., assignor
to The Q & C Company, New York, N. Y., a
corporation of Maine

Application June 3, 1933, Serial No. 674,150

7 Claims. (Cl. 126—180)

This invention relates to grate bars particularly adapted for locomotive fire boxes and has for its object to produce an improved grate bar structure designed successfully to meet the practical requirements of its special use and offer advantages over the types at present used.

Important features of my improvement consist of grate bar sections composed of a rockable supporting member having detachable fuel supporting bars mounted thereon combined with improved securing means for the fuel supporting or grate bars adapted to facilitate the replacement of individual bars while affording security against accidental displacement. To this end the fuel bars are desirably formed with locking shoulders for engagement with a movable key or locking bar designed to be actuated by one of the fuel bars, preferably the endmost of the bars, of the assembly, so as to lock or release all of the bars of a grate section depending upon its position. Associated with the actuated fuel bar there is provided an escapement locking means whereby it is normally secured or locked against displacement whereby under normal conditions all of the fuel bars are secured in position upon the supporting member. In further accordance with my invention, the fuel supporting bars are of special form to provide for indirect passage of the air to the fuel bed in a manner better to promote the combustion by the admission of an abundance of air, while avoiding localized air blast effect under forced draft conditions.

The foregoing and other important features and advantages of my improved structure will be more fully understood by reference to the accompanying drawings wherein like reference characters are applied to the corresponding parts in the several views.

Figure 1 is a view in side elevation illustrating my improved sectional grate bar assembly.

Figure 2 is a plan view thereof.

Figure 3 is a longitudinal, horizontal sectional view on line 3—3 of Figure 1.

Figure 4 is an enlarged cross sectional view taken on line 4—4 of Figure 1.

Figure 5 is a vertical sectional view taken on line 5—5 of Figure 1.

Figure 6 is a partial view in side elevation of my improved grate bar construction showing the endmost grate bar tilted to position for releasing all the separable grate bars and for its removal.

Figure 7 is a partial, vertical, sectional view showing a suitable modification.

In the approved embodiment of the features of my invention as shown in the drawings, the grate

is composed of a plurality of parallel rocking grate bar sections of improved form, each grate bar section consisting of an elongated supporting bar having trunnion bearings at each end and upon which is mounted a series of separable fuel supporting or grate bars formed to provide the air passages to the fuel bed as hereinafter more fully described.

Each supporting bar indicated generally by 1 is of the form of a beam, provided at its ends 10 with bearing trunnions 2—2, the axes of which are substantially coincident with the upper surface of the supporting member so as to provide a depending support whereby the grate bar section by its weight will assume a horizontal position. 15 On its underside it is provided with the usual shaker arm 3 to which connection is made for rocking the grate section. The upper surface of the supporting bar is formed as shown with a series of spaced depressions 4—4 providing spaced 20 bearings for transversely extending, separable fuel supporting or grate bars 5 extending equidistantly to each side of the supporting bar. The grate bars are formed and spaced from each other to provide the air passages to the combustion 25 chamber and are mounted to have a limited rocking movement in a plane transversely of the supporting bar to facilitate rocking or shaking of the grate section and are further mounted upon the bar in a manner whereby they will, by their 30 weight, assume a normal horizontal position and are further formed for engagement with a locking member of improved design adapted for simultaneously releasing all of the grate bars to allow 35 the removal of individual bars merely by vertically lifting them from the supporting member.

The improved design of the grate bars is best shown in Figs. 4 to 6 wherein as shown the grate bars 5 are integrally formed of upper laterally widened fuel supporting portions, having depending web portions 8 and 9 disposed at opposite sides of the supporting bar 1 and spaced to be fitted thereover by a substantially vertical movement. The upper or head portion of the supporting bar 1 is formed of convex curvature and the 45 central bearing surface of the grate bars is of angular form with relation thereto having bearing or rest points upon the supporting bar at points 10 and 11 at opposite sides of the central axis of the supporting bar. As a result the grate 50 bars will normally rest upon the bearing points or lines 10 and 11 and upon rocking thereof, the bearing will shift to one or the other side of the central axis, thereby to have a gravity return to normal horizontal position. Within the spaced 55

depressions of the bar 1, it is provided with central shoulders or bosses 12, of a size to loosely fit within complementary notches 13 in the grate bars to maintain a centralized position of the 5 grate bars upon the supporting bar 1.

As will be noted, the opening defined by the opposed inwardly directed surfaces of the webs 8 and 9, is of a size to loosely encompass the supporting bar 1, thereby to permit rocking of the 10 grate bar transversely of the supporting bar 1 which movement is limited by the engagement of the inwardly directed shoulder portions 14 and 15 of the grate bar webs with opposed surfaces of the supporting bar 1. The web portion 8 of the grate bar is formed with a shoulder 16 adapted to underlie a co-acting shoulder portion 17 of the supporting bar to resist upward displacement of the grate bar unless slightly shifted to the left as shown in Figs. 4 and 5. At its lower end portions 15 the web 8 is received within spaces formed between retaining shoulders 24 integrally formed on the side of the supporting bar 1, the purpose of which is to retain the grate bars in proper vertical position. The opposite depending web 20 portion 9 of the grate bar has its inner wall surface cut out to form an upper inwardly directed retaining shoulder 18 and a lower hook or lock shoulder portion 19, the function of which is to co-act with an improved locking means for securing the grate bars in position upon the supporting bar.

The improved locking means as here shown, comprises a shiftable locking bar adapted in one position to overlie the hook shoulder portions 19 of the grate bars to oppose upward movement thereof and in another position to be non-engaging with the shoulders 19 to allow removal of the grate bars. In the construction as shown, the supporting bar member 1 is at its lower portion 25 formed with a longitudinal slideway or bearing recess 20, formed in its side and providing a bearing for a slidable locking bar 22, provided on its outer face with locking or key projections 23 spaced to correspond with the spacing of the detachable grate bars 5. Adjacent to its end portions and extending from the opposite side of the locking bar 22, it is formed with inwardly projecting retaining lugs 25-26 having enlarged head portions adapted in one position of the bar 30 to be received within enlarged openings 27-28 formed in the supporting bar 1 and to be moved longitudinally within communicating restricted openings 29-30, wherein they interlock to resist lateral separation of the locking bar, while permitting a limited longitudinal movement. To properly limit the normal operating movement of the locking bar at one end thereof, as shown in Fig. 1, it is formed on its under side with a shallow recess 32 within which is received a small 35 stop lug 33 on the upper side of the slide bearing shoulder of the supporting bar. This recess 32 and co-acting lug, limits the movement of the locking bar for normal operation from locking to release position of the locking projections 23, 40 with relation to the grate bar lugs 19, throughout which movement the retaining shoulders 25-26 will be positioned within the restricted openings 29-30 of the locking bar, so as to be retained in assembled relation therewith. Extreme elevation of the end of the locking bar at the recess 32 end thereof, will allow the bar to clear the shoulder 33 at the time of assembling the locking bar with the supporting member 1.

In accordance with a further feature of my 45 invention, provision is made for actuating the

locking bar 22 by means of one of the detachable grate bars the endmost bar at the left end as here shown being employed for the purpose. To this end the locking bar at its end portion is provided with outwardly extended inclined shoulders 35, between them providing an opening for the reception of the shoulder portion 19 of the endmost bar, whereby upon a tilting of the bar as shown in Fig. 6, it will effect longitudinal shifting of the locking bar to release the 10 individual grate bars to allow them to be removed vertically from the supporting member. This arrangement eliminates the function of a locking projection 23 of the locking bar retaining the endmost or actuator grate bar in its assembled relation to the supporting bar 1 and there is accordingly provided special securing means for this end grate bar which consists in providing the laterally projecting retaining shoulders 37-38 on the supporting bar positioned to have an escapement relation to the upper retaining shoulder 18 of the grate bar, whereby when the end bar is in its assembled vertical position the shoulder 37 will oppose upward movement thereof and the shoulder 38 will oppose tilting movement until the end bar is slightly raised to clear said latter shoulder.

There is thus provided a simplified arrangement wherein separable grate bars of identical form are assembled upon a supporting bar with locking provision consisting of but a single movable locking member, having interlocked relation with the supporting bar and providing for the simultaneous locking or release of all of the separable grate bar members by a simple operation and allowing of individual grate bars to be removed from any portion of the bar at will.

A further important and advantageous feature of my present improvements consists in the formation of the fuel supporting upper surface of the grate bar in the manner as shown to provide the upwardly inclined side passages or grooves 40, formed in the side surface of the bars and connected by the cross grooves 41 in the upper surface of the bar and associated therewith the provision of a lateral projecting deflecting flange or shoulder 42, extending horizontally upon one side of each of the grate bars and provided with a series of air openings or notches 43, therein for the passage upwardly of the air to the combustion chamber. The arrangement shown combined with the spacing of the grate bars from each other, is designed to provide the desired cross sectional area of air spacing providing an indirect passage of the air to the upper grate 55 surface which contributes to improved combustion in that the indirect flow permits of the admittance of a relatively larger volume of air with a damped effect while avoiding the localized air blast effect of direct vertical openings 60 which are objectionable under forced draft conditions.

In Fig. 7 there is shown a desirable modified form of the upper bearing surface of the supporting member and coacting under bearing surface of the grate bar designed to obtain the normal return of the bar to horizontal position upon rocking thereof. As here shown, the supporting member 1 is provided centrally on its upper surface with a flattened bearing surface 45 upon which the grate bar rests with a slightly wider co-acting bearing surface. Upon rocking of the grate bar the bearing engagement will be shifted to one or the other side of the central axis thereby to have a normal return by gravity.

Having described my invention, I claim:

1. A rockable grate bar section comprising a supporting bar member and grate bars detachably mounted thereon, said grate bars being formed with locking shoulder portions and a shiftable locking bar carried by the supporting bar, said locking bar being formed with locking projections disposed in one position of the bar to have locking engagement with the shoulder portions of a plurality of the grate bars and simultaneously to release said bars to permit removal thereof when shifted to another position. 5
2. A rockable grate bar section comprising a supporting bar member and grate bars detachably mounted thereon, said grate bars being formed with locking shoulder portions and a shiftable locking bar provided with locking projections disposed to have locking engagement with the shoulder portions of a plurality of the grate bars and simultaneously to release said bars when shifted to another position, said supporting bar and locking bar being formed to have interlocking engagement to maintain an assembled relation and to allow of longitudinal movement of the locking bar with relation to the supporting bar. 10
3. A rockable grate bar section comprising a supporting bar member formed with fulcrum bearings at its end portions and spaced depressions on its upper surface, separable grate bar units supported in said depressions, said grate bar units having depending web portions disposed at opposite sides of the supporting member, one of said web portions being provided with an inwardly extending locking shoulder, a locking slide bar shiftable supported on the supporting member, said locking bar being formed with locking projections adapted in one position of the bar to overlie the grate bar shoulders to oppose removal of the grate bars from the supporting bar and interengaging means between the supporting bar member and the locking bar to limit movement of the latter from locking to release position. 15
4. A rockable grate bar section comprising a supporting member formed at its ends with fulcrum bearings, separable grate bar units mounted upon the supporting member and formed with locking shoulder portions, a locking bar slidably supported upon the supporting member, said locking bar being formed with locking projections adapted in one position of the bar to overlie the grate bar shoulders and having associated with one of the grate bars engaging means there-with operative to effect shifting of the locking bar upon tilting of said latter grate bar to effect simultaneous locking or releasing of other of said bars. 20
5. A rockable grate bar section comprising a supporting member formed at its ends with ful- 25
- crum bearings, having a series of spaced transverse bearings on its upper surface and having laterally extending retaining shoulders, separable grate bar units supported in said transverse bearings and having depending web portions disposed at opposite sides of the supporting member, one of said web portions being engaged by the retaining shoulders to oppose tilting from the vertical thereof, the other of said web portions being provided with an inwardly extending locking shoulder portion, a locking slide bar movably supported on the supporting member, said locking bar being formed with locking projections adapted in one position of the bar to overlie the grate bar shoulders, one of said grate bars being supported to allow of tilting thereof and engaging means between said latter grate bar and the locking bar to effect movement of the locking bar to lock or release the other of the grate bars. 30
6. A rockable grate bar section comprising a supporting member formed at its ends with fulcrum bearings, separable grate bar units mounted upon the supporting member and formed with retaining and locking shoulder portions, a locking bar slidably supported upon the supporting member, said locking bar being formed with locking projections adapted in one position of the bar to overlie the grate bar locking shoulders, said supporting member being formed with retaining shoulders positioned to be engaged by the grate bar retaining shoulder of one of said grate bars normally to oppose removal thereof from the supporting member but to allow removal upon the tilting thereof and engaging means between the latter grate bar and the locking bar for the actuation of the latter. 35
7. A rockable grate bar section comprising a supporting member formed at its ends with fulcrum bearings, having a series of spaced transverse bearings on its upper surface and having laterally extending retaining shoulders, separable grate bars supported in said transverse bearings and having depending web portions disposed at opposite sides of the supporting member, one of said web portions being engaged by the retaining shoulders to oppose tilting from the vertical, the other of said web portions being provided with inwardly directed retaining and locking shoulder portions, a locking bar slidably supported on the supporting member, said locking bar being provided with locking projections adapted in one position of the bar to overlie the locking shoulders, one of the grate bars being supported to allow tilting thereof and having engagement with the locking bar to effect shifting thereof and retaining shoulders on the supporting member positioned to engage the grate bar retaining shoulder of the tiltable grate bar. 40
